UNITED STATES PATENT OFFICE.

EUGENE J. WEEKS AND GEORGE M. CADY, OF JACKSON, MICHIGAN, AS
SIGNORS TO THE CORONET CORSET COMPANY, OF SAME PLACE.

BUSTLE.

SPECIFICATION forming part of Letters Patent No. 292,453, dated January 22, 1884.

Application filed February 24, 1883. (No model.)

To all whom it may concern:

Be it known that we, EUGENE J. WEEKS and GEORGE M. CADY, citizens of the United States, residing at Jackson, in the county of Jackson and State of Michigan, have invented certain new and useful Improvements in Bustles, of which the following is a specification, reference being had therein to the accompanying drawings.

10 Figure 1 is a top or plan view of our invention. Fig. 2 is a perspective view reduced; and Fig. 3 is a transverse section taken on line $x x$, Fig. 1.

One object of our invention is to obviate the 15 tendency which exists in bustles as ordinarily constructed to expand laterally when compressed in a transverse direction, another object being to produce one of greater elasticity, and consequently less liability to injury from 20 the undue compression, than hitherto has been attained, and another object is to promote both economy and durability.

For clearness of description we will refer to the various parts of which the bustle is composed in the position in which they are shown in the drawings, particularly as indicated in Fig. 3, in which the lower and smaller convolution of the spiral springs is indicated as being at the lower ends of the springs, the larger 30 convolutions being at their upper ends.

The structure is formed, preferably, of a single piece of wire, and consists, essentially, of spiral springs B B, combined with a suitable base, C C D D e e, the larger outer convolutions 35 of the coiled springs B being united to the coils E E F F. By an examination of the drawings it will be seen that the angular portions C C D D e e constitute a substantially rectangular base, upon which the spiral springs B B 40 and the coils E E are supported, and that the lower convolutions of the spiral are formed with eyes at a a, through which a rivet, e, passes, this rivet and the hooks f at the inner upper ends of the portions F F serving as ties 45 to maintain the several parts of the structure in proper relation to each other, and it will be observed that the springs are arranged within the planes of the bounding-lines of the substantially rectangular frame or base.

50 In practice we usually commence forming the structure at the central part, (marked A,) and, bending the wire into the spirals, unite these at their lower ends by means of eyes a a and rivet e; then form the bends C C D D d d, all of which are in substantially a common 55 plane. We next carry each end of the wires in an upward transverse direction, as at e e, and form the coils E E, after which we form hooks f f upon the ends F F, and secure them to the upper convolutions of the spirals, preferably by closing down the ends of the hooks, so as to form practically tight eyes. In order to insure the desired outline to the structure, the coils E E may be bent toward the lower 60 angular base-wires and secured to them by loops G G. (See Fig. 3.) The structure may now be covered by any desired fibrous fabric, and may have applied to it such straps, bands, or other appliances as are commonly employed in connection with such articles.

From an examination of the drawings, particularly of Fig. 3, it will be seen that the portion A of the wire, the upper convolutions of the springs, the ends F F, and the coils E E constitute a practically continuous surface, 75 which, commencing at the point marked A, inclines gradually toward the rectangular base portion, with which it may be finally united by the bands G, and that the structure may be compressed by pressure applied to this upper 80 or outer surface without producing any lateral extension in either direction—that is to say, in the direction of the dotted lines $x x$ on Fig. 1, or in a direction transverse thereto.

It will be readily seen that the structure is 85 very elastic and yielding, and therefore very durable.

We do not wish to be restricted to any size of wire or other material, nor to the exact arrangement of spirals, coils, and angular portions here shown, as many modifications there-in might be made without departing from the spirit of our invention, which consists, essentially, in a wire support for a bustle wherein there is a substantially rectangular base, in 95 combination with spiral springs arranged within the bounding-lines of the base.

It will also be seen that by reason of the ends F F being connected to the spirals by means of eyes these ends may be moved to different positions upon said spirals, in order to adjust the position of the coils E E so that they

shall conform to the desired shape of the covering, which forms part of bustles of this class as ordinarily constructed.

It will also be seen that the axes of the spirals are at substantially right angles to the plane of the base.

What we claim is—

1. The bustle-support composed of wire and having a substantially rectangular base, in combination with spiral springs arranged within the bounding-lines of the base, the axes of the springs being substantially at right angles to the plane of the base, substantially as set forth.

15 2. The bustle-support formed of wire and having a substantially rectangular base, in combination with spiral springs arranged within the bounding-lines of the base, and having their axes at substantially right angles to the plane of the base, and the supplemental coils E E, substantially as set forth.

20 3. The bustle-support formed of wire, and having two spiral springs formed of a continuous piece of wire and connected together at 25 their upper and lower ends, substantially as set forth.

25 4. A bustle-support formed of a continuous

piece of wire, bent to form spiral springs, and also bent to constitute a substantially rectangular frame having its plane at right angles 30 to the axes of the springs, substantially as set forth.

5. A bustle-support formed of wire and having spiral springs arranged side by side, and coils E E, adjustably connected to convolutions of the spiral springs, substantially as set forth.

6. A bustle-support formed of wire and having a substantially rectangular base, in combination with spiral springs having their axes 40 at substantially right angles to the plane of the base, one convolution of each spring being connected by a continuous wire and other convolutions of the springs being connected to each other, and the coils E, attached to the convolutions of the springs, substantially as set forth.

In testimony whereof we affix our signatures in presence of two witnesses.

EUGENE J. WEEKS.

GEORGE M. CADY.
